FOLDING MACHINE

Albert F. Shields, Forest Hills, N. Y., assignor to
 S & S Corrugated Paper Machinery Co. Inc.,
 Brooklyn, N. Y., a corporation of New York

Application September 11, 1946, Serial No. 696,085

11 Claims. (Cl. 93—49)

1

My present invention relates to folding machines and more particularly to a folding machine of the type generally shown in my prior Patent 2,336,507, wherein large size corrugated board or other paper blanks are to be passed from a stack through various folding elements and delivered to a tape applying mechanism.

In the making of cartons, it is necessary first to crease and slot the blanks in order properly to prepare them for the folding operation. Heretofore and prior to the advent of a specific folding machine for operating rapidly on blanks, it has been customary to fold these blanks manually and feed them into the taping machine. The folding operation for an ordinary square tubular box comprises bending over the two outer panels on the score lines so that the edges of the panels meet to form a collapsed tube. The maximum speed which can be expected from manual folding is of the order of from 10 to 30 blanks per minute. In addition, where the blanks have been incorrectly creased or scored prior to folding, it becomes necessary for the operator when bringing the edges of the folded panel together to twist the panels around the crease and adjust and reform the crease in order that the tube may be squared properly. This operation is very time consuming when performed manually; also the operator tends readily to place aside and discard blanks the panels of which are visibly askew, thus leading to a great deal of waste and additional operations.

My novel machine has for its primary purpose the rapid folding and delivering of the blanks at a rate ranging upward from 120 a minute to as high as 180 blanks per minute and even higher.

My novel device also embodies elements which will straighten and reform the crease in any blank in which the panels when folded are askew without slowing the rate of folding in any way.

Primarily my present invention is directed toward improvements in the device shown in my Patent 2,336,507 which improvements were invented in order to increase the folding rate of my machine, also to increase the range of the machine with regard to sheet sizes and materials to improve the reliability of operation and also to shorten the set-up time. These improvements include a stacking arrangement which will permit delivery of warped blanks to the folding apparatus, also where the side gages are automatically positioned when the folding width is set; prefolding elements which will start the panels to be folded around their bend line just prior to the point where the blanks reach the folding plates, improved plates which are curved

2

to extend the prefolding action; improved stop means which act on the unfolded portion of the blank for holding the blanks in proper position during folding; improved re-creasing means to re-form the creases in blanks, the panels of which would otherwise be askew; improved means for adjusting the machine to various sizes and arrangements of the blanks; and improved means for simplifying and integrating the drives for the various elements of the machine so that each operation will take place at the proper instant.

Also, my novel machine includes added means to ensure bringing the blanks up to the stop under all conditions and preventing rebound; stripping means to ensure that the folded blanks clear the retracted stop; folding bar limiting rolls to limit deflection of the folding bars and guide the folded blank into the straightening section.

The foregoing and many other objects of my invention will become apparent in the following description and drawings, in which:

Figure 1 is a top plan view of my novel improved folding machine.

Figure 2 is a side view of the novel folding machine of Figure 1.

Figure 3 is a side view partly in cross-section corresponding to the side view of Figure 2 taken on line 3—3 of Figure 1.

Figure 4 is an enlarged side view showing the stacking and feeding arrangement for the blanks to be folded.

Figure 5 is an end view of my novel machine taken from line 5—5 of Figure 2 looking in the direction of the arrows.

Figure 6 is a view partly in cross-section of the front gauge of the stacking device taken from line 6—6 of Figure 4 looking in the direction of the arrows.

Figure 7 is a cross-sectional view showing the manner in which the blank enters the region of the folding plates.

Figure 8 is a cross-sectional view taken on line 8—8 of Figure 4 looking in the direction of the arrows.

Figure 9 is an enlarged top plan view showing the arrangement of the pre-folding means for preparing the panels of the blanks for folding by the folding prints of my invention.

Figure 10 is a side view of the pre-folding means of Figure 9 taken from line 10—10 of Figure 9 looking in the direction of the arrows.

Figure 11 is an end view of the pre-folding means and stop device taken from line 11—11 of Figure 10 looking in the direction of the arrows.

Figure 12 is a side view partly broken away

taken on line 12-12 of Figure 1 showing the means for operating the stop device out of stopping position after the blank has been folded.

Referring now to Figures 1, 2 and 3, a stack of blanks 20 is placed on the bed 22 of the stacking section 21 of the machine between the rear gauge 23 and the front gauge 25. The bottom blank in the stack is fed toward the right by the feed slat 27 through the spaces 30, 30 (Figure 6) between the front gauges 25, 25 and the bar 31 on which the stack is placed. The spaces 30 are adjusted so that they are just high enough to permit one of the blanks 20 to pass through while holding back the remainder of the stack. The blank passing through the spaces 30 passes over the bar 31 and the idling roller 32, the function of which is hereinafter described, and then is pushed by the feed slat 27 between the upper and lower feed rolls 35 and 36 respectively (Figure 3). Feed rolls 35 and 36 engage the blank and carry it forward to the upper and lower feed rolls 37 and 38. Feed roll 38 on the underside of the blank extends across the width of the machine whereas the upper feed roll 37 actually consists of two rollers 37a and 37b (Figure 1) which are adjustable so as to engage only the unfolded panel of the blank; that is, feed rollers 37a and 37b are adjusted so that they are just inside the fold line as defined by the folding bars 39 and 40. This adjustment is hereinafter described in connection with the adjustment of frame 332.

The blanks are then fed by the feed rolls 37 and 38 between the upper and lower feed rolls 41, 42. Upper feed roll 41 actually consists of two feed rolls 41a and 41b occupying the same position respectively as feed rolls 37a and 37b as shown in Figure 1 and simultaneously adjustable with said feed rolls. This adjustment is also hereinafter described in connection with the adjustment of frame 332. The feed roll 42 on the underside is a single roll extending entirely across the machine and is rotatably mounted between the levers 43 which in turn are rotatably mounted on the pins 44 on opposite sides of the machine carried on lugs of the cross-bracket 45. The lower end of cross-bracket 45 has secured thereto arm 46 having an opening through which the spring actuated guide rod 47 passes (all of the foregoing may readily be seen in Figure 3). Compression spring 48 around the guide rod 47 bears between washer 49 on the underside of lever 43 and washer 50 on the upper side of arm 46 and thus biases lever arm 43 upwardly to bias the idling roll of 42 upwardly to tightly press the blank against the upper feed roll 41.

The maximum lift of lever 43 and thus the maximum rise of idling roll of 42 may be controlled by the adjustable nuts 51 on the lower end of the guide rod 47.

Rolls 35 and 38 are also spring biased, in a manner similar to the spring means described for roll 42.

The blank is then carried under the folding bars 39 and 40 and over the feed rolls 53 (see also Figure 10) which are rotatably mounted on each side of the machine on arms 54 rotatably supported on a center coaxial with shaft 55. Each of the arms 54 has an extension 56 on the opposite side of the shaft 55 connected to tension spring 57, which in turn is connected to a stationary lug 58 (Figures 3 and 10). The spring 57 biases the feed rolls 53 upwardly to engage and drive the blank. The feed rolls 53 engage the blank on each side by pressing it up against the folding bars 39 and 40 and thus carry the blank

forward until its front edge engages the stops 73a mounted on stop bars 73. The forward progress of the blank is thus arrested while the feed rolls 53 continue to rotate and press the blank against the stops 73a.

While the blank is in this position with its forward edge against the two stops 73a, the creases or scores on which the fold is to take place are in register with the outer sides of the folding bars 39 and 40. This is, of course, obtained by an appropriate adjustment of the machine as hereinafter described, prior to the beginning of a run and by appropriate stacking of the blanks.

While the blank is in the stop position against stop 73a, the folding plates 60 (Figure 1) which are each held on their respective cross arms 61 are driven around to fold the blank. Each of the cross arms 61 which supports its folding plate 60 is driven by link 62 which connects it to the crank 63, which in turn is driven from the folding blank operating box 64. The drive for folding plate 60 is thus substantially the same as described in my prior Patent 2,336,507.

The folding plate 60 is driven around by the mechanism thus described to fold the side panels of the blank around the folding bars 39 and 40 and to fold them down flat upon the remainder of the blank. The folding operation is facilitated first by reason of the fact that the folding plates 60 and 61 are downwardly bent at 67 in order that the side panels of the blank may readily ride up thereon. Also, the folding operation is further facilitated by means of the deflecting plate 73 on each side (seen specifically in Figures 9 to 11) each of which terminate in an angularly positioned roller 71 so that the side panels are folded up of the order of 25° between plate 73 and roller 71 on each side even before the blank reaches the folding position. The side panels are thus given an initial angularity with respect to the moving blank so that the folding plates need not rotate the side panels through a full 180° but must as shown by an examination of Figure 11 rotate through approximately only 150°.

The stop bars 73 are as shown in Figure 10 supported by the bracket arm 75 which in turn is pivotally supported on the fixed shaft 76 on each side.

The stop bar 73 on each side has a downward extension 78, the lower end of which is connected by eye bolt 79 to the tension spring 80, which in turn is connected to the lug 81 secured to the U-shaped members 22a which are carried by and fixed to the width between the folding boxes and adjusted with them. Accordingly, the stop bar 73 on each side is maintained in raised position by tension spring 80. The U members 22a serve to support the blank while in the folding section and then also serve to strip the folded blank from the stop when it retracts.

The two downward extensions 78 on each side of the machine each carries a roller 84 which is engaged by the lever bar 85a on the levers 85 on shaft 86. After the folding operation has been completed, the shaft 86 is rotated counterclockwise with respect to Figure 10 to rotate the lever 85 counterclockwise and push down the rollers 84 of extensions 78. This pushes down the stop bars 73 which move down with the bracket 75 which in turn rotates about the shaft 76. This in turn pulls down the stops 73a on each side and thus removes the stop members from the leading edge of the blank.

The machine is so arranged and timed that as soon as the stops 73a are depressed by the

5

action of lever 85, slat 90 mounted across the chains 91 moves up into engagement with the rear of the folded blank and moves the blank beneath the hold-down strip 92 which strip is adjustably supported by feed screw 93 operated by knurled knob 94 on the cross bar 95. The hold-down strip 92 is adjusted so that it extends just in front of the stops 73a. The front end is curved upwardly at 92a so that panels which tend to spring up after being folded will be guided down again and their edges brought to abutting position. As soon as the slat 90 on chains 91 engages and moves it forward further through the machine, the guide presses down on the same between the panels and prevents the folded blank from opening up.

The blank is then carried forward between the limiting rolls 100, 101 which as shown in Figure 3 loosely control the position of the delivery end of folding bars 39 and 40. Since the folding bars 39 and 40 are supported from the front frame 332 of the stacking device and since the free or delivery ends of the folding bar are substantially distant from their supports, they may be moved through a small angle.

The rollers 100, 101 above and below respectively each of the folding bars 39 and 40 limit the upward and downward movement of the free ends of the folding bars 39 and 40 so that they will not be flexed to too great an extent. These rollers also serve, in addition to controlling the position of the free ends of the folding bars 39 and 40, to control the blank and hold it in a somewhat central position so that the edges of the blank will be properly engaged by the straightening rolls 110.

The straightening rolls 110 are each mounted on stub shafts (not shown) which in turn are supported on the adjustable plates 112, 112. Straightening rolls 110 on each side are aligned with each other and are provided with grooves as shown in Figure 3 adapted to receive the folded edge of the blank. The plates 112, 112 are adjusted so that the peripheries of the aligned rollers 110 on each side are spaced apart by a distance which is slightly less than the width of the folded blank. The slat 90 forces the blank between the rolls 110 with the edges of the blank riding in the annular grooves on each side. Since the rolls are thus spaced slightly closer together than the width of the blank the crease or fold is adjusted and spread vertically.

The movement of the slat which maintains the rear edge of the blank normal to its direction of travel holds the blank at the correct angles with respect to the rolls 110, so that in a properly folded blank the crease is adjusted regularly on each side. Where the score line was initially incorrect or where the panel was folded improperly, the score lines are adjusted and straightened so that recreasing rolls 120 may then recrease or press the fold properly. The rolls 110 adjust and spread the crease to a greater width at that portion of the blank which has been widened by the skewed folding. As the blank leaves the crease adjusting rolls 110, it passes between the pressure rolls 120, 120 on each side of the machine which recreases the blanks as the blanks are delivered. Since the blank is maintained with its side edges exactly parallel to its path of movement by the slat 90, the recreasing operation performed by recreasing rolls 120 forms the crease in exactly the right position.

I have found that panels which have been

6

skewed so that the trailing or leading edge of the panel projects over the end edge of the main body of the box by more than a quarter of an inch have been straightened and properly recreased by this operation. Blanks which had been improperly scored, so that when folded up the panel would be skewed, have been corrected and straightened during the passage through the folding machine.

My machine, therefore, reduces the waste of blanks and makes it possible to utilize blanks even though they have been improperly or carelessly creased or scored.

This type of recreasing operation has also been described in my prior Patent 2,336,507 wherein several spaced crease adjusting rolls are shown on each side. While spaced crease adjusting rolls have been able properly to recrease and correct skewed blanks, I have found that by placing the crease adjusting rolls 110 in closely spaced relation as shown in Figures 1 and 3, a greater degree of skew may be corrected.

The hold-down is adjusted forward and back in support 94 (Figure 7) by loosening the screw 93a and sliding the slat back and forth; and is adjusted up and down by screw 93. Each of the said slats 90 mounted across the chains 91 has a recess 130 so that it may readily slide or move on either side of the hold-down slat 92.

The folded blanks are preferably delivered to a taping machine and the bar 126a serves to hold down the panels of the folded blank right up to the point of tape application. Side guides 140a are provided to guide the blanks into the straightening section without marring the front corners of the box.

The apparatus comprises, as previously pointed out, a number of improved elements, each of which cooperate with each other and with the entire machine in order to provide for increased speed and facility of operation.

Referring to Figure 5, a variable speed D. C. motor 150 with the sprocket 151 drives the sprocket 152 which is mounted on shaft 153 which carries sprocket 154 of Figure 1. Sprocket 154 provides power to pull the chains 91. Chains 91 are in turn held by idler sprockets 155 on shaft 156 (Figures 1 and 3). Idler sprocket 157 (Figure 3) is adjustably mounted to tighten the chains. Shaft 153 also holds sprocket 160 which in turn drives sprockets 161, 162 and 163 thus driving the lower delivery shaft 141 and the upper delivery shaft 140 and the taper cam shaft 166.

Referring to Figure 1, the end of shaft 153 holds a bevel gear 170 which drives bevel gear 171 on shaft 172. Bevel gear 173 on shaft 172 (also in Figure 12) drives bevel gear 174 on stud 175 and so drives drop-off cam 176 which is mounted on bevel gear 174. Roller 177 on arm 178 engages the periphery of cam 176; thus an oscillatory motion is imparted to lever 178 and to shaft 86 on which it is mounted; the shaft 86 as mentioned before serves to retract the stop 73a. Set screw 180 held in housing 181 engages an arm of lever 178 and serves to limit the angular motion of the lever 178 and also of the shaft 86.

Referring back to Figure 1, the shaft 172 is connected to shaft 200 by means of the coupling 201. Bevel gear 202 on shaft 200 drives bevel gear 203 on shaft 204 which provides power to both of the folding boxes 64. Bevel gear 205 on shaft 200 drives bevel gear 206 on shaft 207 and

thus turns the spur gear 208 which also is keyed to shaft 207.

Referring to Figure 2, gear 208 meshes with gears 209, 210 and 211 and thus drives gears 220, 221 and 222. Gear 222 drives gear 223. It can be seen that by means of this gearing the feed rolls 35, 36, 37, 38 and 41 are all driven. Also that rolls 35 and 38 are pivotally held on the centers of gears 223 and 221 respectively so that these feed rolls when spring biased will 10 adjust themselves to any thickness of blank.

Referring back to Figure 1, gear 230 on shaft 200 drives gear 231 which holds bevel gear 232. Bevel gear 232 drives bevel gear 233 on the kicker drive shaft 234.

Referring to Figure 4, the crank 235 which is keyed to 234 drives link 236 which in turn drives crank 237 and link 238. Link 238 is a pin-connected link which transfers the variable rotary motion of pin 239 on link 237 to a variable reciprocating motion of pin 240 on kicker carriage 241. Carriage 241 carries the kicker bar 242 in such a manner that the bar is adjustable relatively to the carriage by means of the T-shaped member 243 and the screw 244 (see Figure 8). The spring kickers 27 are mounted on the kicker bar 242 in order to obtain adjustment for warped blanks.

All members which engage the edges of the blank are provided with nuts which in turn are 30 driven by screws all of which are driven from a common source on each side of the machine in order to adjust the machine for different widths of blanks.

The motor 300 in Figure 2 drives the shaft 301 through a worm gear reduction 302. Shaft 301 holds a sprocket 303 (Figure 1) which engages a chain 304 which passes over sprockets 305, 306 and 307. Sprockets 305, 306 and 307 drive screws 309 of Figure 10 and 308 and 310 of Figure 1 respectively and these in turn serve to adjust the straightening roll bracket 112, the stop and deflector assembly of Figure 10, and the molding box 64 of Figure 1 respectively. At the other end of shaft 301 is a sprocket 320 which by means of chain 321 drives sprockets 322 and 323. Sprocket 324 is an idler for the purpose of tightening chain 321.

Referring to Figure 6, sprocket 322 is keyed to screw 343 on each side which engages nut 343a of Figure 1 mounted on frame 325. Frame 325 holds the side gauge 326 shown also in Figures 2 and 6. Sprocket 323 is keyed to screw 330 which engages nut 331 on frame 332 shown on Figures 1 and 3. Frame 332 serves to hold front gauge 25 and also the folding guide bar 39. Since the sprocket 322 contains half as many teeth as the sprocket 323 and since their respective screws 343 and 330 have the same lead, the frame 325 which holds the side gauge 326 will be moved twice as far as the frame 332 for a given movement of the chain 321 and of the sprocket 320. The frames 325 and 332 are supported on bars 351 and 352 in Figure 3. These bars are held at both ends by the brackets 353 and 354 (Figure 6) which are mounted on housings 355 and 356 respectively. The side and front gauges on each side are thus simultaneously adjusted.

Referring to Figure 10 in a similar manner, 70 the carriage 312 is mounted on the two bars 76 and 360 which are in turn supported in the side frames of the machine.

In the foregoing I have described my invention only in connection with an illustrative em-

bodiment thereof. Since many modifications and variations of my invention will now be apparent to those skilled in the art, I prefer to be bound not by the specific descriptions herein but only by the appended claims.

I claim:

1. In a folding machine for forming flat collapsed tubular box blanks from flat and scored sheets, said sheets having a pair of longitudinally extending side sections defined by score lines and foldable about said score lines into said collapsed tubular arrangement; stop members mounted on said machine, means for moving said blanks successively against said stop members; means for folding over the side sections; said folding means comprising a pair of oppositely disposed folding plates, means for rotating said plates about an axis parallel to the score lines defining said longitudinally extending side sections, said plates being rotatable and engaging the side sections during rotation, and rotating said side sections into face to face relation with the body of the blank; the ends of the folding plates first engaged by the blank as it moves from the machine being curved away from the folding direction to permit said blank to move into registry with the folding plates while the main body of each of the folding plates is still in the path of movement of the blank, said curved portions of the folding plates deflecting the extending side sections of the blank in the direction of folding to permit said blank to move into position to be folded.

2. In a folding machine for forming flat collapsed tubular box blanks from flat and scored sheets, said sheets having a pair of longitudinally extending side sections defined by score lines and foldable about said score lines into said collapsed tubular arrangement; means for folding over the side sections; said folding means comprising a pair of oppositely disposed folding plates, means for rotating said plates about an axis parallel to the score lines defining said longitudinally extending side sections, said plates being rotatable and engaging the side sections during rotation, and rotating said side sections into face to face relation with the body of the blank; the ends of the folding plates first engaged by the blank as it moves from the machine being curved away from the folding direction to permit said blank to move into registry with the folding plates while the main body of each of the folding plates is still in the path of movement of the blank, said curved portions of the folding plates deflecting the extending side sections of the blank in the direction of folding to permit said blank to move into position to be folded.

3. In a folding machine for forming flat collapsed tubular box blanks from flat and scored sheets, said sheets having a pair of longitudinally extending side sections defined by score lines and foldable about said score lines into said collapsed tubular arrangement; stop members mounted on said machine; means for moving said blanks successively against said stop members, means for folding over the side sections, said folding means comprising a pair of oppositely disposed folding plates, means for rotating said plates about an axis parallel to the score lines defining said longitudinally extending side sections, said plates being rotatable and engaging the side sections during rotation, and rotating said side sections into face to face relation with the body of the blank; a pair of

folding bars extending in the direction of movement of the blank, the outer edges of the folding bars coinciding substantially with the score lines between the main body of the blank and the extending side sections; pivotally mounted longitudinal bars, said stop members being mounted on said longitudinal bars, said longitudinal bars underlying the folding bars, said blank passing between said longitudinal bars and the folding bars; a pair of horizontal parallel plates on each side of the machine, each of said longitudinal bars carrying the stop members riding between a pair of said parallel plates, the upper edges of said parallel plates on each side serving as the support for the blank while it is moved against the stop, said longitudinal members when they are lowered to remove the stop from the path of the blank moving down between the said plates and forcing the leading edge of the blank off the stop as the stop moves down with the longitudinal bars.

4. In a folding machine for forming flat collapsed tubular box blanks from flat and scored sheets, said sheets having a pair of longitudinally extending side sections defined by score lines and foldable about said score lines into said collapsed tubular arrangement; stop members mounted on said machine; means for moving said blanks successively against said stop members, means for folding over the side sections, said folding means comprising a pair of oppositely disposed folding plates, means for rotating said plates about an axis parallel to the score lines defining said longitudinally extending side sections, said plates being rotatable and engaging the side sections during rotation, and rotating said side sections into face to face relation with the body of the blank; a pair of folding bars extending in the direction of movement of the blank, the outer edges of the folding bars coinciding substantially with the score lines between the main body of the blank and the extending side sections; pivotally mounted longitudinal bars, said stop members being mounted on said longitudinal bars, said longitudinal bars underlying the folding bars, said blank passing between said longitudinal bars and the folding bars, the stop members carried by said longitudinal bars being arranged to abut against the portion of the blank between the score lines and also engaging the folding bars to prevent the blank from forcing itself over the stop members, and means for removing the blank from the stops as the stops are lowered.

5. In a folding machine for forming flat collapsed tubular box blanks from flat and scored sheets, said sheets having a pair of longitudinally extending side sections defined by score lines and foldable about said score lines into said collapsed tubular arrangement; stop members mounted on said machine; means for moving said blanks successively against said stop members, means for folding over the side sections, said folding means comprising a pair of oppositely disposed folding plates, means for rotating said plates about an axis parallel to the score lines defining said longitudinally extending side sections, said plates being rotatable and engaging the side sections during rotation, and rotating said side sections into face to face relation with the body of the blank; a pair of folding bars extending in the direction of movement of the blank, the outer edges of the folding bars coinciding substantially with the score lines between the main body of the blank and the ex-

tending side sections; pivotally mounted longitudinal bars, said stop members being mounted on said longitudinal bars, said longitudinal bars underlying the folding bars, said blank passing between said longitudinal bars and the folding bars, a longitudinally extending vertical plate on each side of the machine, each of said longitudinal bars carrying the stop members riding adjacent a vertical plate, the upper edge of said plate on each side serving as the support for the blank while it is moved against the stop, said longitudinal members when they are lowered to remove the stop from the path of the blank moving down adjacent the said plate and forcing the leading edge of the blank off the stop as the stop moves down with the longitudinal bars.

6. In a folding machine for forming flat collapsed tubular box blanks from flat and scored sheets, said sheets having a pair of longitudinally extending side sections defined by score lines and foldable about said score lines into said collapsed tubular arrangement; stop members mounted on said machine; means for moving said blanks successively against said stop members, means for folding over the side sections, said folding means comprising a pair of oppositely disposed folding plates, means for rotating said plates about an axis parallel to the score lines defining said longitudinally extending side sections, said plates being rotatable and engaging the side sections during rotation, and rotating said side sections into face to face relation with the body of the blank; a pair of folding bars extending in the direction of movement of the blank, the outer edges of the folding bars coinciding substantially with the score lines between the main body of the blank and the extending side sections; pivotally mounted longitudinal bars, said stop members being mounted on said longitudinal bars, said longitudinal bars underlying the folding bars, said blank passing between said longitudinal bars and the folding bars; and a feed roll beneath the folding bars and biased upwardly toward the folding bars.

7. In a folding machine for forming flat collapsed tubular box blanks from flat and scored sheets, said sheets having a pair of longitudinally extending side sections defined by score lines and foldable about said score lines into said collapsed tubular arrangement; stop members mounted on said machine; means for moving said blanks successively against said stop members, means for folding over the side sections, said folding means comprising a pair of oppositely disposed folding plates, means for rotating said plates about an axis parallel to the score lines defining said longitudinally extending side sections, said plates being rotatable and engaging the side sections during rotation, and rotating said side sections into face to face relation with the body of the blank; a pair of folding bars extending in the direction of movement of the blank, the outer edges of the folding bars coinciding substantially with the score lines between the main body of the blank and the extending side sections; said stop members being mounted on longitudinal bars, said longitudinal bars underlying the folding bars, said blank passing between said longitudinal bars and the folding bars; apparatus for successively feeding the bottom sheet in a plane parallel to the said sheet from a stack of said sheets into the folding apparatus; a platform for supporting the stack of sheets, side guides for defining the stack

of sheets and front guides for maintaining the stack of sheets in position, said front guides extending vertically above the said platform; a space between the lower ends of the front guides and the platform equal to slightly more than the thickness of one sheet; means in said feeding device adapted to feed out such sheets when such sheets extend in a perfect plane and when such sheets are warped.

8. In a folding machine for forming flat collapsed tubular box blanks from flat and scored sheets, said sheets having a pair of longitudinally extending side sections defined by score lines and foldable about said score lines into said collapsed tubular arrangement; stop members mounted on said machine; means for moving said blanks successively against said stop members, means for folding over the side sections, said folding means comprising a pair of oppositely disposed folding plates, means for rotating said plates about an axis parallel to the score lines defining said longitudinally extending side sections, said plates being rotatable and engaging the side sections during rotation, and rotating said side sections into face to face relation with the body of the blank; a pair of folding bars extending in the direction of movement of the blank, the outer edges of the folding bars coinciding substantially with the score lines between the main body of the blank and the extending side sections; said stop members being mounted on longitudinal bars, said longitudinal bars underlying the folding bars, said blank passing between said longitudinal bars and the folding bars; apparatus for successively feeding the bottom sheet in a plane parallel to the said sheet from a stack of said sheets into the folding apparatus; a platform for supporting the stack of sheets, side guides for defining the stack of sheets and front guides for maintaining the stack of sheets in position, said front guides extending vertically above the said platform; a space between the lower ends of the front guides and the platform equal to slightly more than the thickness of one sheet; means in said feeding device adapted to feed out such sheets when such sheets extend in a perfect plane and when such sheets are warped; an adjustable mounting bracket, the front guides for the sheet feeding apparatus and the folding bars being supported on said bracket.

9. In a folding machine for forming flat collapsed tubular box blanks from flat and scored sheets, said sheets having a pair of longitudinally extending side sections defined by score lines and foldable about said score lines into said collapsed tubular arrangement; stop members mounted on said machine; means for moving said blanks successively against said stop members, means for folding over the side sections, said folding means comprising a pair of oppositely disposed folding plates, means for rotating said plates about an axis parallel to the score lines defining said longitudinally extending side sections, said plates being rotatable and engaging the side sections during rotation, and rotating said side sections into face to face relation with the body of the blank; a pair of folding bars extending in the direction of movement of the blank, the outer edges of the folding bars coinciding substantially with the score lines between the main body of the blank and the extending side sections; said stop members being mounted on longitudinal bars, said longitudinal bars underlying the folding bars, said blank passing between said longitudinal

bars and the folding bars; apparatus for successively feeding the bottom sheet in a plane parallel to the said sheet from a stack of said sheets into the folding apparatus; a platform for supporting the stack of sheets, side guides for defining the stack of sheets and front guides for maintaining the stack of sheets in position, said front guides extending vertically above the said platform; a space between the lower ends of the front guides and the platform equal to slightly more than the thickness of one sheet; means in said feeding device adapted to feed out such sheets when such sheets extend in a perfect plane and when such sheets are warped, the side guides for the sheet feeding apparatus, the folding bars and the folding plates being simultaneously adjustable to blanks of different sizes.

10. In a folding machine for forming flat collapsed tubular box blanks from flat and scored sheets, said sheets having a pair of longitudinally extending side sections defined by score lines and foldable about said score lines into said collapsed tubular arrangement; stop members mounted on said machine; means for moving said blanks successively against said stop members, means for folding over the side sections, said folding means comprising a pair of oppositely disposed folding plates, means for rotating said plates about an axis parallel to the score lines defining said longitudinally extending side sections, said plates being rotatable and engaging the side sections during rotation, and rotating said side sections into face to face relation with the body of the blank; a pair of folding bars extending in the direction of movement of the blank, the outer edges of the folding bars coinciding substantially with the score lines between the main body of the blank and the extending side sections; said stop members being mounted on longitudinal bars, said longitudinal bars underlying the folding bars, said blank passing between said longitudinal bars and the folding bars; apparatus for successively feeding the bottom sheet in a plane parallel to the said sheet from a stack of said sheets into the folding apparatus; a platform for supporting the stack of sheets, side guides for defining the stack of sheets and front guides for maintaining the stack of sheets in position, said front guides extending vertically above the said platform; a space between the lower ends of the front guides and the platform equal to slightly more than the thickness of one sheet; means in said feeding device adapted to feed out such sheets when such sheets extend in a perfect plane and when such sheets are warped; means for simultaneously adjusting all of the elements of the sheet feeding apparatus and the folding apparatus to sheets of different sizes.

11. In a folding machine for forming flat collapsed tubular box blanks from flat and scored sheets, said sheets having a pair of longitudinally extending side sections defined by score lines and foldable about said score lines into said collapsed tubular arrangement; stop members mounted on said machine, means for moving said blanks successively against said stop members; means for folding over the side sections; said folding means comprising a pair of oppositely disposed folding plates, means for rotating said plates about an axis parallel to the score lines defining said longitudinally extending side sections, said plates being rotatable and engaging the side sections during rotation, and rotating said side sections into face to face relation with the body of the blank; the ends of the folding plates first engaged by

the blank as it moves from the machine being curved away from the folding direction to permit said blank to move into registry with the folding plates while the main body of each of the folding plates is still in the path of movement of the blank, said curved portions of the folding plates deflecting the extending side sections of the blank in the direction of folding to permit said blank to move into position to be folded, and a deflecting roller positioned before each of the folding plates to initially deflect the side sections of a blank in the direction of folding to facilitate the passage of the blank between the folding plates.

ALBERT F. SHIELDS.
